UNITED STATES PATENT OFFICE.

EDWARD HARRIGAN, OF TACOMA, WASHINGTON.

ROTARY ENGINE.

No. 879,464.

Specification of Letters Patent.

Patented Feb. 18, 1908.

Application filed January 30, 1907. Serial No. 354,933.

To all whom it may concern:

Be it known that I, EDWARD HARRIGAN, a citizen of the United States of America, and a resident of the city of Tacoma, in the 5 county of Pierce and State of Washington, have invented certain new and useful Improvements in Rotary Engines, of which the following is a specification.

The primary object of my invention is to 10 provide a construction embodying certain improvements over my Patent No. 821,797 which will be specifically referred to as the description progresses.

Referring to the accompanying drawing, 15 forming a part of this specification and in which similar numerals of reference are used to indicate like parts throughout: Figure 1 is a view partly in side elevation and partly in section. Fig. 2 is an end view of the invention, parts being shown in section. Fig. 3 is a view in top plan and, Fig. 4 is a detail view of the abutment.

Reference numeral 1 indicates the casing which is preferably formed in two sections, 20 as shown, and having a continuous bore which is circular in cross section.

2 indicates a carrier fixed to shaft 3 which is journaled in suitable bearings 4 of the casing. The rim of this carrier is fitted between the casing sections and provided with 25 a suitable piston 5 which slides freely in the casing. Each casing section, at the side of the rim of the carrier, is formed with a groove in which suitable packing as 6, is fitted to prevent steam escaping from the casing. 30 Each packing 6 is expansible, the same being hollow and split at one side throughout its length. As now considered, packings 6 are arranged with their split sides in the grooves 35 of the casing, one at each side of the rim of the carrier in contacting relation thereto, and steam is admitted into these packings through conduits 7, whereby to expand the same and thereby serve to enable the bearing 40 of the packings on the rim of the carrier to be a yielding one. The source of supply of steam with which conduits 7 communicate is casing 1, said conduits preferably communicating therewith at opposite sides of 45 abutment 8. This abutment comprises opposite oscillatory members formed with semi-circular cutouts 8' which are adapted to register so that piston 5 can pass therethrough. Component members of the abutment 50 normally stand with their cutouts out of registration and suitable packing 9 on said

members prevents escapement of steam therebetween.

The abutment members are provided at their upper ends with arms 10 which are connected for simultaneous operation by a link 11. The means for oscillating the abutment members consists of a cam 12, fixed to shaft 3, said cam having an external groove in which a roller 13' on the lower end of a lever 13, fulcrumed at 14 rides, and links 15 and 15' the latter of which is pivoted to one of the arms 10 (see Fig. 3).

Reference numeral 16 indicates the steam chest from which ports 17 and 18 lead to the bore of casing 1, ports 17 communicating with the casing at one side of abutment 8 and ports 18 communicating with the casing at the opposite side thereof. In the steam chest are valves 19, 19¹ arranged as in my aforesaid patent so that one valve closes one of the ports 17, (see Fig. 1), while the other valve closes a different port 18. In the inner ports of the respective pairs are oscillatory valves 20, which valves are provided with arms 21 connected by a link 22.

Reference numeral 23 indicates a lever fulcrumed to the casing and having one of its arms connected to link 22 and its other to a rod 24 which is operatively connected to the 85 governor.

The particular form of governor is immaterial to the carrying out of my invention, that shown being of the type illustrated in my patent.

90 The mechanism herein shown for imparting movement to the abutment members as well as the means illustrated for supplying steam to the expansible packings can be readily varied without departing from the 95 spirit of my invention as defined in the appended claims.

Having thus described my invention, what I claim as new and desire to secure by Letters Patent of the United States of America, 100 is:—

1. In a rotary engine, a casing, a rotatable carrier, a piston connected to said carrier and being slidable in said casing, an abutment comprising opposite members mounted for oscillation and formed with cutouts adapted to register, means to oscillate said members, and packing on each of said members, the packing on one of said members engaging that on the other member when the members are turned so that their cutouts are out 110 of registration.

2. In a rotary engine, a casing formed of two sections, a carrier supported for rotation and having its rim projecting between said sections, a piston secured to the rim of the carrier and operating in said casing, the casing sections at the sides of the rim of the carrier being formed with grooves, hollow expansible packing arranged in each of said grooves and bearing on the rim of the carrier, and conduits leading from the casing for supplying steam to the interior of each packing. 30
5. In a rotary engine, a casing, a rotatable carrier, a piston secured to said carrier and being slideable in said casing, coacting oscillatory abutment members mounted in said casing and formed with cutouts adapted to register, a cam rotatable with the carrier and having an external groove, a lever fulcrumed on the casing and having a bearing part engaged in the groove of said cam, and means operated by said lever for simultaneously oscillating said abutment members. 35
10. In a rotary engine, a casing formed of two sections, a carrier supported for rotation and having its rim projecting between said sections, a piston secured to the rim of the carrier and operating in said casing, expansible packing on opposite sides of the rim of the carrier, and conduits leading from the casing for supplying steam to the interior of said packing. 40
15. In a rotary engine, a casing formed of two sections, a carrier supported for rotation and having its rim projecting between said sections, a piston secured to the rim of the carrier and operating in said casing, expansible packing on opposite sides of the rim of the carrier, and conduits leading from the casing for supplying steam to the interior of said packing. 45
20. In a rotary engine, a casing formed of two sections, a carrier supported for rotation and having its rim projecting between said sections, a piston secured to the rim of the
- 25.

carrier and operating in said casing, the casing sections at the sides of the rim of the carrier being formed with grooves, hollow expansible packing arranged in each of said grooves and bearing on the rim of the carrier, and conduits leading from the casing for supplying steam to the interior of each packing.

5. In a rotary engine, a casing, a rotatable carrier, a piston secured to said carrier and being slideable in said casing, coacting oscillatory abutment members mounted in said casing and formed with cutouts adapted to register, a cam rotatable with the carrier and having an external groove, a lever fulcrumed on the casing and having a bearing part engaged in the groove of said cam, and means operated by said lever for simultaneously oscillating said abutment members.

Signed at Tacoma, Washington this 4" 45
day of October 1906.

EDWARD HARRIGAN.
